UNITED STATES PATENT OFFICE

LEO J. LAMBERT, OF SALEM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FOLDING MACHINE

Application filed October 16, 1924. Serial No. 743,932.

The present invention relates to folding machines, and more particularly to machines for folding a binding strip around the edge of a boot or shoe upper to which it is attached.

5 The chief object of the invention is to improve upon present-day machines of the above-described character, to the end that their construction may be simplified and their cost of production reduced.

10 With this and other objects in view, the nature of which will be made clear in the course of the following description, the invention consists of the folding machine a preferred embodiment of which is hereinafter described, 15 illustrated in the accompanying drawings, and defined in the appended claims.

In the accompanying drawings, Fig. 1 is a perspective, with parts broken away for clearness, of a machine constructed according to a preferred embodiment of the present invention; Fig. 2 is a side elevation of the same, partly in longitudinal section; Fig. 3 is a perspective of a portion of the machine, upon a larger scale; Fig. 4 is a detail plan, also enlarged, illustrating a step in the operation of the machine; Fig. 5 is a vertical section taken upon the line 5—5 of Fig. 2, looking in the direction of the arrows; Figs. 6, 7 and 8 are enlarged vertical sections taken, respectively, 25 upon the lines 6—6, 7—7 and 8—8, respectively, of Fig. 11; Figs. 9 and 10 are enlarged perspectives illustrating two steps in the operation of the illustrative machine; Fig. 11 is a perspective of the upper, forward portion 30 of the machine; Fig. 12 is an enlarged vertical section taken upon line 12—12 of Fig. 11 looking in the direction of the arrows; Fig. 13 is an enlarged perspective, partly broken away, of a portion of the mechanism shown 35 at the left of Fig. 3; and Fig. 14 is a perspective of a portion of the mechanism shown in Fig. 13, but with various elements separated from one another, and with parts broken away, for clearness.

45 The invention is illustrated in the accompanying drawings in connection with the folding of a binding strip 2, Figs. 4, 6 to 10, and 12, of cloth, silk and the like, around the edge 4 of a sheet of leather or other material 50 6, such as a boot or shoe upper. An edge 8 of

the binding strip is sewed to a face 10 of the shoe upper along the edge 4, so that the sheet and the strip extend at an angle to each other from the secured-together edges 4 and 8. The stitches are shown at 12 as extending 55 preferably through, or over and around, a reinforcing cord 14 positioned upon the other face 16 of the shoe upper, along the edge 4. It will be understood that the invention is 60 equally applicable to other articles than that which is herein chosen for purposes of illustration, and the elements of the article need not necessarily be of the relative dimensions shown. It may be desirable, for example, to fold an element of relatively large dimension 65 over the edge of an element of relatively small dimension. For definiteness, the element 70 that is to be folded will hereinafter be referred to in the specification and the claims as the "strip", and the element about the edge of which the strip is to be folded will be herein-after referred to as the "sheet", "stock", "upper", "work", etc., though the adopted terminology may not be strictly applicable to the 75 specific article which may be under considera-tion. With this understanding, the chief ob-ject of the invention is to fold properly a "strip", such as the binding strip 2, from the position illustrated, for example, in Figs. 6, 7, 8 and 12, into the position illustrated at the 80 left of Figs. 9 and 10.

The shoe upper is initially placed in the preferred machine upon a platform or support 24, Figs. 1, 2 and 4 to 12, with the face 10 of the upper in contact with the upper 85 surface of the support. The support is provided with a comparatively sharp edge 25 beyond which the strip 2 is adapted to be disposed, as illustrated in Fig. 12, with the portions of the strip that are adjacent to the 90 stitches 12 below the said upper surface of the support. Rearward of the support edge 25, the support is provided with a second edge 27, to one side of the edge 25, and sep-arated therefrom by a space 29, as shown 95 more particularly in Fig. 11. Beneath the edge 27, the support is hollowed out, the hollow being gradually inclined first, as shown at 31, Fig. 6, then curving over more at 33, Fig. 7, and finally becoming quite restricted 100

in area, and of sharper curvature as shown at 35, Fig. 8.

The sheet is adapted to be advanced through the machine step by step by a feed point 30 and a cooperating feed block 41. As 5 the sheet is thus advanced, the hollow 31, 33, 35 engages the strip and gradually, but firmly, forces it outward, from the position illustrated in Fig. 6 to the position shown in Fig.

10 8, which latter position it substantially occupies at the time that it reaches the space 29. When it is advanced beyond this space, the comparatively sharp edge 25 bites into the angle between the sheet and the strip close to 15 the stitches as shown in Fig. 12. The space 29 permits the sharp edge to work more effectively than if the edges 27 and 25 were continuous. As will be clear from a comparison of Figs. 8 and 12, the sharp edge 25 extends 20 farther to the right than does the edge 27.

In this condition, the stock is advanced to a plow 34 that bends the free edge 26 of the strip nearly vertical, as illustrated in Fig. 12. The plow is mounted upon a stationary 25 bracket 61. Successive portions of the strip 2 are thus treated and thus successively presented to the action of a folder 32. The folder 32 moves at first parallel to the plane of the upper, until it reaches the position illustrated 30 in Fig. 9, and then obliquely toward the plane of the upper, from the position of Fig. 9 to that of Fig. 10. Toward the end of its travel, the folder engages a portion of the strip just forward of the plow 34, as is illustrated in 35 Figs. 9 and 10. This oblique movement of the folder results in a pulling action, upon the portion of the strip 2 that it engages. The folder thus not only folds the margin, but pulls it, as well. The pulling effect is increased 40 towards the end of the movement of the folder. This combined folding and pulling action would not, however, by itself, suffice, for the strip would have a tendency to slip past the folder, instead of being pulled 45 along by it. To prevent this happening, therefore, the folder is caused to engage the strip against a downwardly inclined face 246 of a member 153 at the end of its movement. The member 153 may conveniently be the retainer. During the subsequent movement of 50 the folder, the folder positively drags the folded strip frictionally past the retainer 153, preventing any slipping, and safely laying the portion of the margin which it engages 55 flat into contact with the face 16 of the upper. At the end of its travel, the folder presses down hard against the strip. This rubbing and pressing action of the folder will cause the strip to adhere to the face 16 of the upper, 60 the strip having been previously cemented to effect this object. No additional presser is necessary.

This accomplished, the plow is retracted. The lower feed block 41 and the upper feed point 30 thereupon grip the upper between 65

them, and advance the stock another step. The feed point and the feed block release their hold on the upper just after the retainer has gripped the upper. They thereupon retrace their movement, during the action of the folder, the retainer 153 helping to hold the stock stationary. The cycle of operation is then repeated. The margin thus becomes folded step by step.

The feed mechanism of the illustrative machine, comprising the feed block 41 and the feed point 30, is driven from a driving shaft 66, and is described more completely in co-pending applications by Andrew R. Ridderstrom, Serial No. 352,987, filed January 21, 1920, and Serial No. 407,336, filed September 1, 1920. The former matured, on February 24, 1925, into Letters Patent No. 1,527,395. The feed block 41 is shown more particularly in Fig. 2 as integral with a plate 134. The plate 134 is mounted upon a rocking support 94. The rocking support is pivotally mounted about a rod 96 that is secured to a stationary support 95 by a screw 98. The rocking support 94 is provided with a diagonally disposed cylindrical opening 100, Figs. 1 and 2, within which is slidably mounted a diagonally cylindrical block 102 the upper flat face of which is substantially horizontal. The cylindrical block 102 is adapted to be actuated by an eccentric or crank pin 106 of the driving shaft 66. The eccentric or crank pin is rotatably mounted in the block 102. Rotative movement of the shaft 66 will be converted by the eccentric into combined sliding and oscillating or rotative movement of the block 102 and this, in turn, will effect a rocking movement of the rocking support about the rod 96.

The feed point 30 is pivotally mounted at 110 upon the rocking support 94 so as to be rocked therewith and with the lower feed block 41, and is normally maintained in contact with the feed block by a coiled spring 112.

As the driving shaft 66 is rotated, the rocking support 94 is rocked back and forth, imparting an oscillating movement to the lower feed block 41 and the upper feed point 30 which are carried thereby. This effects an intermittent separation of the feed point 30 from the feed block 41 through the action of the cylindrical block 102. Further description will be found in the said applications.

The folder 32 and its actuating mechanism are very similar to those illustrated, described and claimed in a copending application Serial No. 705,228, filed April 9, 1924. It is driven from a spiral cam 154 that is fixed to the shaft 66. The rotation of the cam 154 effects the reciprocation of a pin 152 that is engaged thereby and that is fixed to a sliding member 150. A link 161 is pivoted at an end 63 to the sliding member 150, and at the other end 65 to an arm 67. The arm 67 is rigidly connected to a segmental gear 71 that is loose-

ly mounted upon a pin 69. The gear 71 meshes with a rack 73 that is carried on the under side of a horizontally disposed support 75. The support 75 and the rack 73 carried thereby are disposed substantially at right angles to the line of feed. Rocking of the gear 71 is therefore converted into a reciprocating movement of the support 75 in a horizontal plane and at right angles to the line of feed. The folder 32 is mounted upon the support 75 so as to move therewith. This construction, therefore, causes the folder to reciprocate horizontally along the line 26 at right angles to the line of feed.

15 A sub-support 77, Fig. 13, is pivoted to the support 75 about a pivot 79, Fig. 14. The folder is pivoted to the sub-support 77 about a pivot 81 that is perpendicular to the pivot 79. When the folder reaches a predetermined position in its path of movement, its tail 83 engages an abutment 85, Fig. 3. Further travel of the support 75 therefore causes the abutment to act against the tail 83, effecting the pivotal movement of the folder about the pivot 81. As the support 75 continues its travel, the folder is caused to ride over the downwardly inclined face 246 of the retainer 153, the retainer being situated in the line of travel of the folder for this purpose, and being shaped to effect this result. This engagement of the folder with the retainer is permitted by the sub-support 77 pivoting about the pivot 79 in a direction at right angles to the direction of pivotal movement of the folder about the pivot 81.

Upon the return movement of the support 75, a spring 87 effects the return of the sub-support 77 to its normal position, and a spring 89 performs a similar function for the folder 32. The spring 87 is shown as a plurality of leaf springs fastened at one end between fixed abutments 91 and engaging at the other end an abutment 93 that is integral with the sub-support 77. The spring 89 is also constituted of a plurality of leaf springs and is fastened at one end 195 to a support 365 and its other end engages a hook 97 that is integral with the folder 32. The end 195 may be fastened by riveting, or in any other desired manner.

55 The abutment 85 is rendered yielding to permit the folder to yield when occasion requires. To this end, it is slidably mounted in a groove 99 that is disposed in the forward portion of the frame of the machine, at right angles to the direction of feed, and parallel to the groove in which the support 75 is slidably mounted. A block 103, Fig. 3, is fastened to a projecting horn 206 of the support 95 by pins 105, and acts as a common guide between the slidably mounted members 75 and 85. A coil spring 107 is interposed between the block 103 and the abutment 85 to hold the abutment normally in the extended position indicated in the drawings. The

spring 107 is stronger than the springs 87 and 89, so that it will not be compressed until after a force more unyielding than the springs 87 and 89 is opposed to the spring 107. An adjustable stop 109 at the other end 70 of the abutment adjustably engages the abutment to adjustably limit the normal position of the abutment. This stop adjustably determines the time of engagement of the tail 83 by the abutment 85, and therefore controls the degree of movement of the folder 32 about its pivots 81 and 79. This movement, in turn, determines the degree of pull of the folder against the strip 2.

15 Summarizing the operation of the preferred machine, as thus far described, the shoe upper is advanced over the support 24, step by step, by the feed point 30 and the feed block 41; the retainer 153 helps to hold the stock stationary during pauses in the feed; and the folder 32 is actuated, first in a plane parallel to the line of feed along a line at right angles to the line of feed, and later obliquely to the plane of the material, against the retainer, during pauses in the feed, to 80 fold successive portions of the strip 2, step by step after the strip has first been initially folded, as previously described. A gage 436 secured by a screw at 438, is provided to engage the edge 4 of the stock.

20 Among the simplifications in structure of the present invention is a novel retainer-operating mechanism. The retainer 153 is carried upon a shaft 198 that is adjustably clutched at 220, 222 to a shaft 182, as is described in the said copending application, Serial No. 407,336. A coil spring 216 yieldingly connects the shafts 182 and 198 together. The shaft 182 is provided with an arm 184 having a freely pivoted roller 186 that is engaged by a cam 188 upon the shaft 66. Rotation of the shaft 66 thus effects a 25 lifting of the retainer 153 through a rise in the cam 188, and the spring 216 returns the retainer when the roller 186 engages other 90 portions of the cam 188.

30 The support 95 is provided with a bearing 108 through which and through a bearing 67 of the machine frame the shaft 66 extends. The support 95 rests upon a lug 205 of the machine frame, and is held in position by pins 207 that extend through oppositely disposed perforated lugs 109 of the frame, and into correspondingly disposed openings 111 of the support 95.

35 Many details of the illustrative machine have not been illustrated herein, and many illustrated parts have not been described, because unnecessary to an understanding of the present invention, and because full particulars may be obtained in the aforesaid applications. The elements of novelty, furthermore, though fully explained, are by no means restricted to the exact embodiments thereof that are illustrated and described 120 125 130

herein. Modifications and changes will readily occur to persons skilled in the art, and all such are considered to fall within the scope of the invention, as defined in the appended claims.

5. What is claimed is:

1. A machine for folding a strip around the edge of a sheet material to one face of which, along the said edge, an edge of the strip is secured so that the sheet and the strip extend from the secured-together edges at an angle to each other, the said machine having, in combination, a support, a member for engaging successive portions of the sheet near the secured-together edges and for holding the sheet against the support, means for engaging portions of the strip adjacent to the said successively held portions of the sheet, and means for actuating the strip-engaging means to drag the engaged portions of the strip into contact with the other face of the sheet.

2. A machine for holding a strip around the edge of a sheet of material to one face of which, along the said edge, an edge of the strip is secured so that the sheet and the strip extend from the secured-together edges at an angle to each other, the said machine having, in combination, a support, a member for engaging the sheet near the secured-together edges and for holding the sheet against the support, means for moving portions of the unsecured edge of the strip across the secured-together edges, and means for engaging the moved portions of the strip and dragging them into engagement with the member and past the member into contact with the other face of the sheet.

3. A machine for folding a strip around the edge of a sheet of material to one face of which, along the said edge, an edge of the strip is secured so that the sheet and the strip extend from the secured-together edges at an angle to each other, the said machine having, in combination, means for moving portions of the unsecured edge of the strip across the secured-together edges, a member, a folder, and means for actuating the folder to engage the moved portions of the strip and to fold them into engagement with the member and past the member into contact with the other face of the sheet.

4. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip step by step, a retainer for holding the sheet against movement during pauses in the feed, means for moving portions of the unsecured edge of the strip across the secured-together edges, a folder, and means for actuating the folder during

pauses in the feed to engage the moved portions of the strip and to fold the engaged portions into engagement with the retainer and past the retainer into contact with the other face of the sheet.

5. A machine for folding a strip around the edge of a sheet of material to one face of which, along the said edge, an edge of the strip is secured so that the sheet and strip extend from the secured-together edges at an angle to each other, the said machine having, in combination, a support, means for feeding the sheet and the strip over the support, means for moving portions of the unsecured edge of the strip across the secured-together edges when the said portions reach a predetermined position upon the support, a member, a folder, and means for actuating the folder to engage the moved portions of the strip and to fold them into engagement with the member and past the member into contact with the other face of the sheet when the sheet and the strip are fed to a second predetermined position upon the support.

6. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, and means adapted to be actuated in a plane substantially parallel to the support to engage the strip and move it into contact with the other face of the sheet.

7. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, and a single means adapted to engage the strip and move it into contact with the other face of the sheet.

8. A machine for folding a strip around the edge of a sheet of material to one face of which, along the said edge, an edge of the strip is secured so that the sheet and the strip extend from the secured-together edges at an angle to each other, the said machine

- having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, and means for feeding the sheet and the strip to the said portion of the support edge, the support edge having a second portion rearward of the first-named portion in the line of feed, there being an opening between the two portions, a member for engaging the sheet near the secured-together edges at a point adjacent to the said portion of the support edge, and means for engaging portions of the strip and dragging them into engagement with the member and past the member into contact with the other face of the sheet. 70
9. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, means for feeding the sheet and the strip to the said portion of the support edge, the support edge having a second portion rearward of the first-named portion in the line of feed, there being an opening between the two portions and means for moving the strip into contact with the other face of the sheet. 80
10. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, means for feeding the sheet and the strip to the said portion of the support edge, the support edge having a second portion rearward of the first-named portion in the line of feed, there being an opening between the two portions and means for moving the strip into contact with the other face of the sheet. 85
11. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, a member for engaging the sheet near the secured-together edges at a point adjacent to the said portion of the support edge, and means for engaging portions of the strip and dragging them into engagement with the member and past the member into contact with the other face of the sheet. 90
12. A machine of the class described having, in combination, a folder, means for reciprocating the folder, a shaft having a cam, means adapted to be reciprocated by the cam during the rotation of the shaft, and means controlled by the cam reciprocated means for actuating the folder reciprocating means. 95
13. A machine of the class described having, in combination, a folder, a shaft having a cam, means adapted to be reciprocated by the cam during the rotation of the shaft, the folder having a rack, a pivoted segmental gear meshing with the rack, and a link connecting the gear with the reciprocated means, whereby the gear is rocked about its pivotal point to effect the reciprocation of the folder. 100
14. A machine for folding a strip around the edge of a sheet of material to one face of which, along the said edge, an edge of the strip is secured so that the sheet and the strip extend from the secured-together edges at an angle to each other, the said machine having, in combination, a folder, and means for actuating the folder substantially parallel to the plane of the sheet to cause the folder to engage a portion of the strip and for thereupon actuating the folder towards the other face of the sheet to fold the engaged portion of the strip into contact with the said other face of the sheet. 105
15. A machine for folding a strip around the edge of a sheet of material to one face of which, along the said edge, an edge of the strip is secured so that the sheet and the strip extend from the secured-together edges at an angle to each other, the said machine having, in combination, means for moving portions of the unsecured edge of the strip across the secured-together edges, a folder for engaging successive portions of the moved strip, a member and means for actuating the folder past the member, the folder and the member being constructed and arranged to engage the said portions of the strip frictionally between them during the actuation of the folder past the member to cause the said portions of the strip to be dragged frictionally past the member. 110
16. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, means for feeding the sheet and the strip to the said portion of the support edge, the support edge having a second portion rearward of the first-named portion in the line of feed, there being an opening between the two portions, a member for engaging the sheet near the secured-together edges at a point adjacent to the said portion of the support edge, and means for engaging portions of the strip and dragging them into engagement with the member and past the member into contact with the other face of the sheet. 115
17. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, means for feeding the sheet and the strip to the said portion of the support edge, the support edge having a second portion rearward of the first-named portion in the line of feed, there being an opening between the two portions, a member for engaging the sheet near the secured-together edges at a point adjacent to the said portion of the support edge, and means for engaging portions of the strip and dragging them into engagement with the member and past the member into contact with the other face of the sheet. 120
18. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, a portion of the support edge being adapted to engage the sheet and the strip in the said angle, means for feeding the sheet and the strip to the said portion of the support edge, the support edge having a second portion rearward of the first-named portion in the line of feed, there being an opening between the two portions, a member for engaging the sheet near the secured-together edges at a point adjacent to the said portion of the support edge, and means for engaging portions of the strip and dragging them into engagement with the member and past the member into contact with the other face of the sheet. 125

16. A machine of the class described having, in combination, a retainer, a shaft having a cam, and means for biasing the retainer towards a predetermined position, the cam being adapted to actuate the retainer in opposition to the biasing means during the rotation of the shaft.

17. A folding machine having, in combination, means for feeding material step by step, means for folding the material, a retainer for holding the material against movement during pauses in the feed, a spring tending to maintain the retainer in effective position, and a shaft having a cam, the cam being adapted to actuate the retainer in opposition to the force exerted by the spring during the rotation of the shaft.

18. A machine of the class described having, in combination, a frame having a bearing, opposed openings and a lug, a support adapted to rest upon the lug and having opposed openings adapted to register with the first-named openings, means extending through the openings for maintaining the support upon the frame, means for feeding material mounted upon the support, the support having a bearing, and a shaft for actuating the feeding means mounted in the bearings.

19. A folding machine having, in combination, a frame having a bearing and a lug, a support adapted to rest upon the lug, means for securing the support to the frame, means for feeding material step by step, means for holding the material against movement during pauses in the feed, means for folding the material, the support having a bearing, and a shaft for actuating the feeding, holding and folding means mounted in the bearings.

20. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, means for feeding the sheet and the strip over the support, a portion of the support edge being adapted to engage the sheet and the strip in the said angle, a plow situated forward of the said portion of the support edge in the line of feed for folding the strip around the secured-together edges, and means situated forward of the plow in the line of feed and adapted to be actuated in a plane substantially parallel to the support to engage the folded strip and move it into contact with the other face of the sheet.

21. A machine for folding a strip around the edge of a sheet material to one face of which, along the said edge, an edge of the strip is secured so that the sheet and the strip

extend from the secured-together edges at an angle to each other, the said machine having, in combination, a support over which the sheet and the strip are adapted to be fed, a member for engaging successive portions of the sheet near the secured-together edges to hold the sheet stationary against the support, means for engaging portions of the strip adjacent to the said successive portions of the sheet while the sheet is held stationary against the support, means for actuating the strip-engaging means while the sheet is held stationary against the support to drag the engaged portions of the strip into contact with the other face of the sheet, and means for automatically relatively actuating the member and the support towards and from each other first to hold the sheet stationary against the support and then to release the sheet to permit it to be fed over the support.

22. A machine for folding a strip around the edge of a sheet of material to one face of which, along the said edge, an edge of the strip is secured so that the sheet and the strip extend from the secured-together edges at an angle to each other, the said machine having, in combination, a support, a member for engaging the sheet near the secured-together edges to hold the sheet against the support, means for moving portions of the unsecured edge of the strip across the secured-together edges into substantially the plane of the sheet, means for engaging the moved portions of the strip and dragging them into engagement with the member and past the member into contact with the other face of the sheet, and means for relatively actuating the member and the support towards and from each other to hold the sheet against the support and to release the sheet.

23. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, the support being gradually inclined adjacent to the said edge to engage the strip and gradually move it outward towards a position across the secured-together edges.

24. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support,

the support having an edge beyond which the strip is adapted to be disposed to one side of the said surface, the support being gradually inclined adjacent to the said edge to engage the strip and gradually move it outward towards a position across the secured-together edges, and means for engaging the strip and moving it into contact with the other face of the sheet.

25. A machine for folding a strip around the edge of a sheet of material to one face of which, along the said edge, an edge of the strip is secured so that the sheet and the strip extend from the secured-together edges at an angle to each other, the said machine having, in combination, a support upon which the sheet is adapted to rest with the said one face in contact with the surface of the support, the support having an edge beyond which the strip is adapted to be disposed to one side of the said surface, the support being hollowed out at a gradual incline adjacent to a portion of the said edge to engage the strip and gradually move it outward towards a position across the secured-together edges, a second portion of the said edge disposed forward of the first-named portion in the line of feed being adapted to engage the sheet and the strip in the said angle, and means for moving the strip into contact with the other face of the sheet.

26. A machine for folding a strip around the edge of a sheet of material to one face of which, along the said edge, an edge of the strip is secured so that the sheet and the strip extend from the secured-together edges at an angle to each other, the said machine having, in combination, a folder for engaging successive portions of the strip, a member having an inclined face, and means for actuating the folder past the member, first in one direction and then in another direction past the inclined face, the folder and the member being constructed and arranged to engage the said portions of the strip frictionally between them during the actuation of the folder past the member to cause the said portions of the strip to be dragged frictionally past the member.

50. 27. A machine for folding a strip around the edge of a sheet material to one face of which, along the said edge, an edge of the strip is secured so that the sheet and the strip extend from the secured-together edges at an angle to each other, the said machine having, in combination, a support, means for engaging successive portions of the strip near the secured-together edges, and means for actuating the strip-engaging means first in one direction to engage the said successive portions of the strip and to drag the engaged portions of the strip into contact with the other face of the sheet and then in another direction to return the strip-engaging means without engaging the strip.

28. A machine for folding a strip around the edge of a sheet of material to one face of which, along the said edge, an edge of the strip is secured so that the sheet and the strip extend from the secured-together edges at an angle to each other, the said machine having, in combination, a support, means for moving portions of the unsecured edge of the strip across the secured-together edges, reciprocating means for engaging the moved portions of the strip and dragging them into contact with the other face of the sheet when actuated in one direction and for releasing the strip when actuated in the opposite direction, and means for reciprocating the reciprocating

29. A machine for folding a strip around the edge of a sheet of material to one face of which, along the said edge, an edge of the strip is secured so that the sheet and the strip extend from the secured-together edges at an angle to each other, the said machine having, in combination, a support, means for feeding the sheet and the strip over the support, a folder, and means for actuating the folder first in one direction substantially parallel to the support to engage the successive portions of the strip and to fold them into contact with the other face of the sheet, and then in another direction to return the folder without engaging the strip.

30. A machine for folding a strip around the edge of a sheet of material to one face of which, along the said edge, an edge of the strip is secured so that the sheet and the strip extend from the secured-together edges at an angle to each other, the said machine having, in combination, a folder for engaging successive portions of the strip, a member and means for actuating the folder first in one direction and then in another direction past the member and into contact with the other face of the sheet, the folder and the member being constructed and arranged to engage the said portions of the strip frictionally between them during the actuation of the folder past the member to cause the said portions of the strip to be dragged frictionally past the member and into contact with the said other face of the sheet.

along a path above the support to drag the engaged portions of the strip into contact with the other face of the sheet, and then in another direction to return the strip-engaging means without engaging the sheet.

5. In testimony whereof, I have hereunto subscribed my name this 15th day of October, 1924.

LEO J. LAMBERT.
